UNITED STATES PATENT OFFICE.

THEODORE W. FOSTER, OF PROVIDENCE, RHODE ISLAND.

DESIGN FOR A HANDLE FOR SCISSORS.

SPECIFICATION forming part of Design No. 28,529, dated May 3, 1898.

Application filed March 31, 1898. Serial No. 676,005. Term of patent 7 years.

To all whom it may concern:

Be it known that I, THEODORE W. FOSTER, of Providence, in the county of Providence and State of Rhode Island, have invented and produced a new and original Design for the Handles of Scissors and Similar Articles, of which the following is a specification, reference being had to the accompanying drawing, forming part thereof.

10 The drawing is a side view of a pair of scissors, showing my design.

The leading and material feature of my design consists in the raised ornamentation of the handles, in which strings of graduated beads extend along and between foliated marginal scrolls.

In the drawing, A indicates the scissors, and B B the handles, which are exact duplicates, being ornamented by the same design.

20 The end of the handle is ornamented with the double-beaded band 2. Along the inner margin extends the raised elongated bulb 3 and on the outer margin the foliated scroll 4, the graduated string of beads 5 extending along 25 the center. The foliated scroll 6 extends

along the inner margin to the rounded portion 7 of the finger-loop, and a graduated string of beads extends along the center of that portion of the handle. The scrolled bead 8 extends along the opposite margin of the finger-loop, having a string of beads along its inner curved side. The foliation 9 extends from one end of the scrolled bead 8 to the rounded portion of the finger-loop, spreading out fan-shaped at the end of the foliation, while from 30 the opposite end of the scrolled bead 8 extends the elongated leaves 10 to merge with the end of the foliated scroll 4.

Having thus described my invention, what I claim as new, and desire to secure by Letters 35 Patent, is—

The design for the handles of scissors or similar articles herein shown and described.

In witness whereof I have hereunto set my hand.

THEODORE W. FOSTER.
